UNITED STATES PATENT OFFICE.

LOUIS N. MOSS, OF NEW YORK, N. Y.

VENTILATING WINDOW SHADE AND FIXTURE.

1,094,917.

Specification of Letters Patent. Patented Apr. 28, 1914.

Application filed October 20, 1913. Serial No. 796,116.

To all whom it may concern:

Be it known that I, Louis N. Moss, a citizen of the United States, and a resident of the borough of Manhattan, city, county, and State of New York, have invented certain new and useful Improvements in Ventilating Window Shades and Fixtures, of which the following is a specification.

In my concurrent application No. 788,559, filed Sept. 8th, 1913, I show and describe means for admitting air through the lower portion of a window sash for purposes of effecting ventilation without raising said sash—the sash itself being of special construction. In the present case I seek to attain similar results of privacy with ventilation, when an ordinary lower window sash is raised, by means of an air deflecting and sight-obscuring screen or curtain and supporting side brackets or fixtures of special construction, all as hereinafter described and claimed specifically—distinctive features being the pivotal support of an automatic roller curtain below the upper inner edge of the window sill and the provision of a plurality of seats on the jambs of the frame for the support of the curtain rod at different inclinations and horizontal levels, whereby different areas of opening may not only be covered so as to obstruct observation therethrough, but also whereby the incoming air may be controlled and deflected upward at different angles of inclination for the purpose of regulating ventilation. This I accomplish by means which are simple, cheap, and effective, and which do not interfere with the use or manipulation of the window sash in the ordinary way. Furthermore the shade or screen is readily mounted upon or dismounted from the bracket fixtures which are permanently attached to the jambs of the window frame, thus giving free access to the window for cleaning and similar purposes and rendering the whole window space available in case of emergency. Its adaptability to existing windows of ordinary construction renders my device available and effective where more complicated and expensive means of ventilation &c. would be undesirable or prohibitory.

In the accompanying drawings, Figure 1, is an elevation of the inner side of the lower portion of a window frame and sash showing the practical application of my invention. Fig. 2, is a sectional elevation taken upon plane of line 2—2 Fig. 1; Fig. 3, is

a face elevation of the left hand jamb bracket plate; Fig. 4, a similar view of the right hand jamb bracket plate; Fig. 5, is a sectional detail showing one end of the shade rod seated in one of the jamb brackets.

F represents a window frame of any ordinary or desired construction having the usual sill S the upper inner edge s', of which is slightly above the seat s², of the lower bar a, of the lower sash A, when closed—said sash, of course being counterbalanced and sliding in a vertical way in the usual manner.

Right and left hand bracket plates B, B, are situated respectively on the opposed sides of the frame jambs f', f'', being screwed thereto or otherwise permanently secured in position. These bracket plates B, B, are essentially duplicates of each other except that they face in opposite directions; and they are so positioned as to coincide with each other in details horizontally. Each is formed with a socket b, b, for the reception of the end pivot of an automatic curtain roller C, of the "Hartshorn" or other well known type, the socket on the right side of the frame being slotted to admit and hold the flattened pivot or trunnion of the spring spindle in the ordinary manner. Each bracket plate B, is formed with a vertical runway b', b', for an end of the curtain rod c, which rod is preferably round in cross section or has its ends rounded to fit and travel in said vertical runways b', b', as well as in the lateral ways b², b³, in the lower side walls of which are formed the semi-circular seat recesses b^x, b^x, any of which the ends of the curtain rod c, fit. Each bracket plate B, is also formed with a comparatively broad flange b⁴, b⁴, extending inward toward the center of the window for the purpose of covering and concealing the spaces between the vertical edges of the curtain and the jambs or rather between said vertical edges of the curtain and the bracket plates themselves. These flanges b⁴, b⁴, being inclined upward and inward also deflect any air admitted at the vertical edges of the curtain; and they sustain said edges should the curtain be deflected or bent inward by excess of external wind pressure. The flat flanges b⁴, b⁴, approximate only say one and a half inches in width, and being practically the only parts of the brackets visible from the interior, present no objectionable appearance, especially if the brackets are painted to correspond

with the window frame. Hence their use as permanent fixtures is admissible especially as they do not protrude into or contact the sight and light area; and when the curtain 5 C', is lowered and wound upon the roller C, the latter being below the upper edge s', of the sill, the whole contrivance is invisible from the outside of the window, and neither curtain nor roller obstructs the view. When 10 however the lower sash is raised to admit air as in Figs. 1 and 2 for instance, the curtain may be correspondingly raised to cover the opening and obstruct direct observation therethrough, at the same time acting as a 15 deflector to direct the inlet of air upward into the apartment, thus preventing direct and objectionable drafts and tending to diffuse the fresh air throughout the apartment in the most effective and approved manner.

20 I have shown two lateral ways b², b³, and series of seat recesses b^x, b^x, on each bracket although it is obvious that more may be provided if desired. By the use of seating recesses at different horizontal levels the curtain 25 may obviously be raised and supported at corresponding levels according to the degree of aperture created by the raising of the lower sash. Thus in Figs. 1 and 2 the curtain C', and rod c, are indicated in solid lines 30 as raised and the rod seated in horizontally coincident recesses b^x, b^x, in the lower lateral ways b², while in dotted lines they are shown as raised and the rod seated in corresponding recess seats in the upper lateral guide ways 35 b³. The inclination also of the curtain may be varied as indicated in Fig. 2, to regulate the admission and deflection of the air as hereinbefore set forth.

It is to be understood that the ends of the 40 curtain rod c, protrude beyond the vertical edges of the curtain C', sufficiently to enter and be controlled by the guide ways b', b²,

b³, and that the cross section of said ends of the rod c, conform more or less to the shape of the seating recesses b^x, b^x, although the 45 shape of rod or recess is not material provided they are adapted to the purpose described.

What I claim as my invention and desire to secure by Letters Patent is,

1. The combination of the jamb bracket plates formed with roller trunnion sockets, vertical guide ways, and lateral guide ways, the lower side walls of which latter are formed with seating recesses, and a spring 55 roller curtain mounted on and between said brackets and provided with a curtain rod the ends of which protrude beyond the vertical edges of the curtain, engage the said vertical and lateral ways in the jamb bracket 60 plates, and are adapted to be seated in the said recesses formed for their reception in the lateral guide ways as herein set forth.

2. The combination of the jamb bracket plates formed with roller trunnion sockets, 65 vertical guide ways, and lateral guide ways, the lower side walls of which latter are formed with seating recesses, and a spring roller curtain mounted on and between said brackets and provided with a curtain rod 70 the ends of which protrude beyond the vertical edges of the curtain, engage the said vertical and lateral ways in the jamb bracket plates, and are adapted to be seated in the said recesses formed for their reception in 75 the lateral guide ways, said bracket plates being also formed with inturned flanges adapted to overlap and conceal the vertical edges of the curtain when raised, as and for the purpose set forth.

LOUIS N. MOSS.
